ELECTRIC WATER HEATER OF THE
STORAGE TYPEArthur Robert Draffin, Camberwell, Melbourne,
Victoria, AustraliaApplication December 26, 1944, Serial No. 569,840
In Australia December 13, 1943

11 Claims. (Cl. 219—39)

1

This invention relates to electric water heaters of the storage type, designed to provide for a substantially continuous supply of hot water for domestic and other purposes and more especially to such installations which operate upon electric current supplied on an off peak or restricted hour tariff (sometimes known as night heating) and under a higher or ordinary domestic, commercial or industrial tariff (sometimes known as day heating).

So far as concerns the manner of generating and delivering the hot water, such storage heaters may be said to fall into two main classes, i. e. those which operate upon the "displacement" or "pressure" principle according to which cold water is fed into the bottom of the storage chamber and hot water is taken off from the top, and those which operate upon the "falling level" or "spill over" principle according to which the hot water is delivered or drawn off from near the bottom of the storage vessel.

I consider that the displacement or pressure principle is to be preferred for various reasons, primarily in that it provides a better operating efficiency, which is of paramount importance. In addition, there is the physical advantage that the storage vessel of a "displacement or pressure" type heater may be installed in practically any position such as under the floor, on the floor, in a cupboard, or in the roof of a building, whereas with the falling level type of heater, the storage vessel requires to be elevated above the highest draw off point or tap of the system.

There are numerous types of heaters which operate upon the aforesaid "displacement or pressure" principle. The salient features of the four main types of such heaters will now be briefly described as such description will assist a better understanding of the present invention and the important advances which arise therefrom.

Type A.—According to this type a circulation electric heater is arranged externally of the storage vessel and progressively heats all of the water in the latter by a circulation of the water from the bottom of the vessel through the heater and into the top of the vessel. Satisfactory results are obtainable when operating upon a continuous heating tariff but it is found when operating during the off-peak or restricted hour period there is a very great difference in temperature between the hot water at the top of the vessel and the water at the bottom of the vessel, at the end of the heating period. Thus when hot water is being drawn off and the electric current is

2

switched off, the difference in temperature is most noticeable and low temperature water is likely to be drawn off at a comparatively early stage. In cases where a thermostat device is fitted, it is located near the bottom of the storage vessel but such device is of no practical use when operating upon the ordinary tariff unless it is desired that the entire body of water should be heated.

10 *Type B.*—According to this type an electric heating element is immersed in the water near the bottom of the storage vessel and heats the entire body of water during the off-peak or restricted hour period. Notwithstanding the use of 15 a throw-over switch for replenishment when operating upon the ordinary tariff, a long delay occurs before hot water at a desirable temperature is available for drawing off. This delay is due to the fact that the element has to transmit 20 its heat into the main body of water and thus, all of the water has to be heated before any hot water can be drawn off. Similarly to type A, type B is frequently fitted with a thermostat device near the bottom of the vessel, but this device 25 switches off the current only when the whole of the storage vessel has been heated.

Type C.—According to this type, two separate heating elements are employed, one being immersed in the water at or near the bottom of the 30 vessel and the other element, usually known as an upper or booster element, is arranged within the vessel near the top thereof and is intended to replenish the supply of hot water at the upper part of the vessel to meet an urgent demand. If 35 the quantity of water above the upper or booster element amounts to say 10 gallons then, while the installation represents an improvement upon types A and B, it suffers from the disability that it does not make sufficiently hot water available 40 for drawing off until substantially the whole 10 gallons of water has been heated throughout. In this type, a thermostat device is fitted near the bottom of the storage vessel to control the heat during the off-peak or restricted hour period, 45 but the upper or booster element is either switched on or off by hand, or if it is desired to be rendered automatic in operation, then an additional thermostat has to be fitted.

Type D.—In this case a heating element is 50 immersed near the bottom of the vessel and is so arranged that a proportion of the heat is transmitted into the main body of water, while the remainder of the heat is transmitted to a confined body of water which passes by way of an external 55 tube to the top of the vessel. The heating ele-

ment, when operating under the restricted hour tariff heats the whole of the water in the storage vessel although there is a slight temperature variance between the top and the bottom at the conclusion of the heating period. When the supply of hot water approaches exhaustion during daytime use, replenishment of hot water is effected by operating a throw-over switch whereupon the electric current is charged for at the ordinary tariff. A proportion of the heated water is delivered to the top of the storage vessel ready for drawing off, but a considerable proportion of the heat is still transmitted direct to the main body of water. Thus, while this type represents an improvement over the previously mentioned types, it still does not replenish hot water at the top of the vessel with sufficient rapidity. It is customary to provide a thermostat device near the bottom of the vessel for automatically switching off the current when the entire body of water has been raised to a given temperature. This is effective for the off-peak or restricted hour tariff heating but if the current is carelessly or otherwise left switched on after replenishing the supply of hot water during operation upon the ordinary tariff, the thermostat will not switch off the current until the entire body of water has been heated to the predetermined temperature notwithstanding that only a relatively small amount of hot water may be required for immediate use. This is, of course, wasteful and uneconomic.

The present invention aims to overcome the foregoing disadvantages and disabilities in a simple and practical manner and to provide for the utmost efficiency, convenience, reliability and economy in the operation of storage heaters of the kind in question.

More specifically the invention, while employing only a single heating element and a single thermostat control device, provides for the entire body of water to be heated to an even temperature throughout, which is ideal especially when operating on the off-peak or restricted hour tariff, and also provides, as and when required, for the most rapid replenishment of hot water at the top of the storage vessel so that it becomes readily available to meet a sudden demand or emergency.

In order to accomplish this and certain other desirable objects as will be explained more fully hereinafter, I employ a single heating element of the water circulating type and connect it with a hot water storage vessel and in a water flow circuit which includes a hot water control valve or diverter device. In one condition this device directs the heated water from the circulatory heater into the lower part of the storage vessel so that the entire body of water is gradually brought to a desired temperature, and, in another condition, diverts all of the heated water from the heater directly into the top part of the vessel, so that hot water is almost instantaneously or, at least, very quickly available at any draw off tap of the system, notwithstanding that the major portion of the water in the vessel is cool or well below a desirable high temperature.

The water control valve or diverter device is preferably arranged to be brought into action automatically upon switching over to operation upon the ordinary tariff, while a single thermostat device is arranged to exercise control over the heating element at all times, i. e. whether it is operating under the off-peak (night-time) tariff or ordinary (day-time) tariff.

The above and various other objects, features and advantages of the invention will now be de-

scribed with reference to one practical embodiment illustrated in the accompanying drawing in which—

Figure 1 is a vertical elevation, partly in section.

Figure 2 is an enlarged sectional elevation of the hot water control valve or diverter device and associated parts.

An installation in accordance with the invention includes a cylinder or vessel 2 of appropriate capacity to serve as a hot water reservoir. This vessel is surrounded by a lagging 3 of appropriate heat insulation material and has a cold water inlet 4 at its bottom connected with an overhead cold water supply tank (not shown) which, as usual, may be fitted with a ball-cock device or the like.

A single electric heating element 6 of the water circulating type is located in any suitable position preferably immediately beneath the bottom of the storage vessel. The heating element casing 7 is surrounded by a jacket 8 one end of which is connected by a pipe 8a with the bottom of the storage vessel near the point where the cold feed water enters the vessel. A baffle (not shown) may be provided within the lower part of the vessel to prevent the incoming feed water from mixing with the hot water in the upper part of the vessel.

The heater water jacket 8 should be inclined slightly towards its other or outlet end from which a pipe or conduit 9 extends upwardly and may be said to have three branches. One branch 10 leads horizontally into the storage vessel at a relatively slight distance above the bottom thereof. A second branch 11 continues vertically upwards and enters the top of the storage vessel preferably adjacent the hot water outlet 2a which may have the usual exhaust pipe (not shown) associated therewith. The third branch 12 extends horizontally outwards in alignment with the first branch and is connected to the water control valve or diverter device 13 as best seen in Figure 2. These three pipes or branches should extend through the heat insulating material 3 around the storage vessel so as to avoid dissipation of heat.

As illustrated, the device 13 comprises a relatively small capacity water chamber 14 into the upper part of which the third mentioned branch 12, or a tail piece 12a connected thereto, opens. Around the exterior of the lower part of this water chamber there is clamped a relatively low wattage electric heating coil 15, suitably insulated, and which may be adapted to be energised only when the installation is operating under the ordinary tariff. In such cases this heating coil may be operatively connected with a throw-over switch.

Retained within the lower part of the chamber 14 is an expandable bellows 16 containing a suitable quantity of an appropriate substance which has a high rate of expansion when subjected to heat. Upstanding from the head or top of these bellows is a rod 17 connected by a pivoted bell crank lever 18 with a horizontal rod 19 extending from a plunger 20 which is disposed in the third branch 12 and has a tapered or conical nose 21 adapted to make contact with a correspondingly shaped seating 22 in the first branch 10. A spring 23 may be associated with the before-mentioned parts in order to yieldingly oppose expansion of the bellows device and to retract the plunger 20 from the seating 22 of branch 10. The plunger should be a good sliding fit within the third branch but it is preferably tapered away as at 24 and has an end portion or tail piece 24a of nor-

mal diameter at the rear of the tapered part 24.

Only one thermostat control device is required according to this invention, and such device, which may be of any suitable form and suitably connected in the electric circuit, is preferably located within a tube 25 closed at its inner end and projecting horizontally into the vessel at a relatively short distance from the top.

When the installation is in use under the off-peak tariff the plunger 20 will, by reason of the spring 23 and the collapsed condition of the bellows 16, be withdrawn from the seating 22 in branch pipe 10 as seen in unbroken lines in Figure 2. Thus, hot water from the heating element jacket will flow through branch 10 into the lower portion of the storage vessel so that the entire body of water therein will be gradually brought up to a substantially uniform temperature. When this has been effected to the required temperature, the supply of electric current to the heating element will be automatically cut-off by the thermostat device.

If and when the supply of hot water in the storage vessel has become exhausted or is approaching exhaustion and hot water is urgently required at any draw-off point in the system, as may frequently happen in day-time, then the low wattage heating coil is brought into action. The heat produced by this coil rapidly heats the water in the chamber 14 and when such water reaches a suitable temperature the bellows device 16 expands, and, through medium of the aforesaid rods and lever, moves the plunger 20 along the third branch 12 so that the cone or like shaped nose 21 of the plunger contacts with the seating 22 at the inner end of branch 10, as indicated by broken lines in Figure 2. As a result, the hot water from the heating element cannot now enter the water storage vessel through branch 10 but passes around the tapered portion 23 of the plunger and travels upwardly through the second branch 11 into the top of the storage vessel so that the heated water is practically instantly available for drawing off.

By tapering the plunger as aforesaid and arranging for such tapered portion to come adjacent the upper end of pipe 9, there is a desirable restriction in the pathway for the hot water which ensures it reaching the top of the vessel at the desired temperature. There are several advantages in adopting such method of restriction, in relation to the usual method of requiring the water to pass through a small fixed orifice or hole. Thus, there is no likelihood of the restricted pathway becoming blocked by foreign matter in the water, and any matter that may be deposited around the pathway will be removed by the movement of the plunger.

When the throw-over switch is returned to the off-peak position, the low wattage heat coil is simultaneously switched off so that the water in chamber 14 will cool and the pressure of the contained chemical or other substance in the bellows will be reduced so that the associated spring 23 will force the bellows back to normal and at the same time cause the plunger to be withdrawn from the seating at the inner end of the branch 10 whereby direct communication is re-established between the heating element jacket and the lower part of the storage vessel.

If the throw-over switch is left on in the normal tariff position, then the current supply to the heating element will be automatically switched off by the thermostat device after a predetermined quantity of hot water has accumulated in

the upper part of the storage vessel. After an interval of time the thermostat will again switch on the current where the water surrounding it has dropped appreciably in temperature. This automatic switching on and off action will be repeated until eventually all the water is heated.

It will be apparent from the foregoing that the invention permits of full advantage being taken of both off-peak and normal tariffs and, by virtue of the hot water control valve or diverter, enables hot water to be obtained at any time at any draw off point in the system without wastage of electric current, in a most economical way in that such hot water is delivered directly from the heating element jacket into the top of the storage vessel.

In addition to the ability to quickly replenish the supply of hot water at ordinary tariff, the diverter device also enables, if it is so desired a portion only of the water to be heated at the off-peak or restricted hour tariff. This is effected by moving the usual throw-over switch to the off-peak position and switching the low wattage heating coil 15 into circuit. Thereupon the water in the upper part of the storage vessel will be heated and as soon as it has reached the desired temperature the thermostat will automatically cause the current to the heating element to be initially switched off.

It will be noted that a small diameter pipe 26 leads from pipe 9 into the water chamber 14 and that another small diameter pipe 27 leads from the rear part of pipe 12 upwardly into pipe 11. The primary purpose of the pipes 26, 27 is to prevent steam accumulation and overheating of the water in chamber 14 when the coil 15 is switched on. Under such condition, and with the plunger moved onto its seating, the two pipes provide for a small by-pass or circulatory flow of hot water from pipe 9, through pipe 26 the chamber 14 and pipe 27, into pipe 11. The tail piece 24a of the plunger will, at this stage, be located between pipe 27 and branch 11 as indicated by broken lines in Figure 2.

Until the tail piece 24a moves to the right past pipe 27 as aforesaid there will not be any circulation of hot water through chamber 14 and this is an advantage as it will lead to quick heating of the water in chamber and a quick movement of the plunger against seating 22.

It is to be understood that the construction of the hot water control or diverter device 13 may be varied in many respects. For instance, the heating coil 15 could be replaced by a solenoid appropriately connected in the electric circuit and arranged to actuate the plunger 20 or other suitable valve through suitable linkage, upon operation of the change over switch. Alternatively, a plunger or other suitable valve could be adopted for manual operation.

Having now described my invention what I claim as new and desire to secure by Letters Patent is:

1. In a water heater of the storage type suitable for operation under the off-peak and the ordinary tariffs of electric supply, a hot water storage vessel, a heating element of the water circulating type having a water inlet connected with the lower part of said vessel, a thermostat control device for said heating element, and a water flow circuit extending between a hot water outlet of said heating element and upper and lower hot water inlets of said vessel, said circuit having interposed therein the control device which, selectively, directs heated water exclusively from the heating element into the lower part of said vessel

so that the entire body of water therein is gradually raised to a desired even temperature throughout, or exclusively directs all of the hot water from the heating element into the top part of the vessel so as to effect a rapid development of hot water for immediate withdrawal.

2. In a water heater, as claimed in claim 1, wherein said water flow circuit includes a pipe extending upwardly from the hot water outlet of said heating element, a first branch extending from said pipe into the lower part of the storage vessel, a second branch extending into the top of the storage vessel, and a third branch for interconnecting said first and second branches, a valve member being provided and selectively operable to cut off exclusively communication between the first branch and the second branch, maintaining the first branch open to said pipe, or to exclusively cut off communication between said pipe and the first branch to cause the pipe to communicate with said second branch.

3. In a water heater, a combination as claimed in claim 1, wherein said control device includes a relatively small capacity water chamber connected in said flow circuit and heated by a relatively low wattage coil, a heat expansive bellows in said chamber, a valve for controlling the flow of hot water from said heating element exclusively to the lower part or to the top of said vessel, and operative connection between said bellows and said valve.

4. In a water heater, a combination as claimed in claim 1, wherein said control device includes a relatively small capacity water chamber connected in said flow circuit and heated by a relatively low wattage coil, a heat expansive bellows in said chamber, a valve for controlling the flow of hot water from said heating element exclusively to the lower part or exclusively to the top of said vessel, and operative connections between said bellows and said valve, said bellows being retained within said water chamber with its upper free end connected to a rod carrying said valve member.

5. In a water heater, a combination as claimed in claim 1, wherein said water flow circuit includes a pipe extending upwardly from the hot water outlet of said heating element, a first branch extending from said pipe into the lower part of the storage vessel, a second branch extending into the top of the storage vessel, and a third branch interconnecting said first and second branches, a valve member being provided and operative selectively to exclusively cut off communication between the first branch and the second branch while maintaining the first branch open to said pipe, or to exclusively cut off communication between said pipe and the first branch and maintain the pipe in communication with said second branch by way of said third branch, said valve member including a plunger having a tapered portion to restrict communication between said pipe leading from the heating element and said second branch when the valve is in one selected position.

6. In a water heater, a combination as claimed in claim 1, wherein said water flow circuit includes a pipe extending upwardly from the hot water outlet of said heating element, a first branch extending from said pipe into the lower part of the storage vessel, a second branch extending into the top of the storage vessel, and a third branch for interconnecting said first and

5 second branches, a valve member selectively operable to exclusively cut off communication between the first branch and the second branch while maintaining the first branch open to said pipe, or to exclusively cut off communication between said pipe and the first branch while maintaining the pipe in communication with said second branch by way of said third branch, said valve member including a plunger having a tapered portion to restrict communication between said pipe leading from the heating element and said second branch when the valve is in one selected position, said plunger having a tail piece of normal diameter spaced rearwardly from said tapered portion.

7. A water heater as claimed in claim 1, wherein said hot water control device is operable to direct hot water exclusively into the top of the storage vessel automatically upon the operation of a switch for changing over from off-peak tariff to ordinary tariff.

8. A water heater as claimed in claim 1, wherein said heating element is located adjacent the bottom of said vessel, and wherein said thermostat device is positioned within the upper part of said vessel and is adapted to control the supply of current to the heating element both when hot water from the heating element is directed to the bottom or to the top of the vessel and irrespective of whether the apparatus is operating under the off-peak tariff or the ordinary tariff.

9. An improved water heater of the storage type, including a hot water storage vessel, a heating element located beneath the vessel and disposed within a casing, a water jacket surrounding said casing, an inlet pipe extending from the lower part of the vessel into the one end of said jacket, a hot water outlet pipe leading upwardly from the other end of said jacket, a first branch extending from said outlet pipe into the lower part of the vessel, a second branch extending from said outlet pipe into the top of the storage vessel and a control device operative selectively to place said hot water outlet pipe into exclusive communication with said first branch or with said second branch as may be desired.

10. An improved water heater as claimed in claim 9, wherein a thermostat device is arranged within and at an appropriate distance beneath the top of said storage vessel and is operatively connected with said heating element so as to control its operation irrespective of the selected positions of said control device.

11. In a water heater, a combination as claimed in claim 1, wherein said control device includes a relatively small capacity water chamber connected in said flow circuit to be heated by a relatively low wattage coil, a heat expansive bellows in said chamber, a valve for controlling the flow of hot water from said heating element exclusively to the lower part or to the top of said vessel, an operative connection between said bellows and said valve, and a relatively small diameter pipe establishing communication between said hot water outlet from the heating element and said water chamber and another relatively small diameter pipe for establishing communication between said chamber and the top part of said storage vessel when said control device is in one selected position.

ARTHUR ROBERT DRAFFIN.
